COLLAPSIBLE VALVE FOR DISPENSING APPARATUS AND THE LIKE

David A. McCowan, Toronto, Ontario, Canada

Application August 2, 1949, Serial No. 108,182

4 Claims. (Cl. 251—5)

1

My invention relates in general to liquid dispensing devices, and in particular to the valve mechanisms of such devices.

It is well known to those skilled in the art that in liquid dispensing devices which are used for dispensing liquids for human consumption, it is of the utmost importance that the valve construction be very simple and that for sanitary reasons all parts thereof may be quickly and thoroughly cleaned.

It is therefore a principal object of my invention to provide a valve for dispensing devices which may be readily removed by the operator from the tank or container.

Another object of my device is to provide valve mechanism which is so simple that it may be easily and thoroughly cleansed by passing running water through it.

Another object is to provide a valve having no parts requiring grinding or close fitting, and one which is very durable in operation.

A further object is to provide a valve mechanism for dispensing devices which shall be of such construction that the valve parts thereof may be easily and quickly renewed at little expense.

The above objects and advantages have been accomplished by the device shown in the accompanying drawing, of which:

Fig. 1 is a side fragmentary sectional elevation of a liquid container with my device attached thereto;

Fig. 2 is a slightly enlarged sectional elevation taken through the vertical center line of the device and indicated by line II—II of Fig. 3;

Fig. 3 is a side elevation of my valve mechanism showing it removed from the tank and ready to be cleaned;

Fig. 4 is a bottom plan view of my invention with the housing cap removed;

Fig. 5 is an isometric perspective view of the pressure members of my device;

Fig. 6 is a face view of a modified form of operating lever;

Fig. 7 is a side sectional view of the form of invention shown in Fig. 6 and is taken on line VII—VII of that figure; and,

Fig. 8 is a fragmentary sectional view of my device taken on line VIII—VIII of Fig. 4.

My device is designed generally for dispensing liquids for human consumption. It is shown in use upon a liquid container 10 which is conveniently supported by a standard 11.

The container with which my invention is to be used is preferably formed with an outlet fit-

ting 12 having a flange 13 which fits into a recess 14. This recess is formed by a depression in the bottom 15 of the tank, thereby forming an annular flange 16. The fitting is formed with a sleeve portion 20 which extends down below the bottom of the flange 16, and a clamping ring 21 is screw-threaded to the lower end thereof. This ring is in spaced relation with the annular flange 16 of the bottom of the container, and the flange 22 of a coupling member 23 is disposed in this space. This coupling member serves to connect the valve mechanism 17 to the container.

My valve 17 comprises a housing 24 of cylindrical shape and formed at its upper end with a screw-threaded neck 25 with which the internally screw-threaded portion of the clamping member 23 engages. A packing washer 28 is disposed between the bottom of the clamping ring 21 and the upper face of the neck 25 of the body part so as to make a fluid-tight joint at this place. The neck 25 of the body part is formed with an annular bore 26 in which is mounted a rigid sleeve 30. This sleeve is flared over at its upper end 31 to form a fluid-tight joint between it and the neck of the housing. The sleeve is provided with a downwardly extending end 27 which is disposed within the enlarged chamber of the housing. The lower end of the housing is formed with a downwardly pointing mouth 33 which is closed by means of a housing cap 34. The cap is engaged with the housing by means of suitable screw-threads so that it may be readily removed by the operator at will. The mouth 33 is preferably larger than the diameter of the rigid sleeve for reasons to be hereinafter described.

The valve mechanism of my device comprises a flexible sleeve 35 which has its upper end engaged with the downwardly extending end 27 of the rigid sleeve 30, and its lower end disposed in an annular opening 36 formed in the housing cap 34. Spring pressed means are provided for pinching the flexible tube to shut-off the flow of liquid, and such means may comprise a stationary pressure member 40 which is carried by the body 24 and is preferably located within a slot 41 formed in the side of the body. This stationary pressure member, as clearly shown in Figs. 4 and 5, is provided with a substantially straight tube-engaging edge portion 43 which is extended into and occupies a position near the axial centerline of the enlarged chamber of the housing so that when the tube 35 is compressed to its closed position it will be disposed substan-

tially at the center of the housing and the aperture of the cap. The stationary member is also formed with two spaced legs 42 thereby providing opposite guiding surfaces 43. A movable pressure member 44 is also provided which has its inner end portion slidably disposed between the guiding surfaces 43 of the stationary pressure member. The inner edge of this member is substantially straight and is formed with a rounded surface 47 which is substantially parallel with the tube-engaging edge portion of the stationary member for pinching the flexible tube 35 from both sides thereof. The movable pressure member 44 is urged inwardly toward the stationary pressure member by means of two tension springs 45. The inner end of each of these springs is disposed within a slot 46 formed in the side wall of the housing 24, and each is held in place by means of a pin 50 carried by the body. The outer end of each spring is mounted upon a pin 51 carried at the outer end of the movable pressure member. These springs are arranged one on each side of and preferably straddle a slot 52 formed in the outer end of the movable pressure member. The actuating lever 53 of my device is disposed within this slot and has its upper end pivotally mounted within a slot 54 formed in an arm 55 which is preferably screw-threaded to the side of the housing. The lower end of the lever is provided with a transverse member 56 against which the tumbler or other receptacle is pressed when it is desired to dispense liquid, as shown in Fig. 1.

The stationary pressure member 40 may be secured within the slot 41 of the body in any desired manner, but I preferably provide two pins 60 which are carried by the housing and which pass through suitable registering apertures 64 formed in the stationary pressure member. Any tendency for these pins 60 or the pins 50 for the springs to become dislocated will be prevented by the presence of the housing cap 34, the flange of which is large enough to extend over the lower exposed ends of these pins.

When my invention is to be adapted for use in connection with paper cups, it is desirable to increase the area of the transverse member of the actuating lever. Such a construction is shown in Figs. 6 and 7 where the actuating lever 61 is formed with a transverse member 62 which extends upwardly for some distance along the face of the lever. It is also provided with an outwardly extending ledge 63 upon which the cup may be rested when being filled.

From the foregoing it will be obvious that since the stationary and movable members of my valve have substantially straight coacting surfaces, the pinching action upon the tube which closes the valve requires but little pressure so that the valve may be readily opened by relatively light pressure against the actuating valve. Furthermore, should the flexible tube 35 become deteriorated, it may be readily removed from the housing by first removing the housing cap 34. After the old tube has been detached from the lower end 21 of the rigid sleeve 30, a new tube may be inserted in the open mouth of the housing and engaged with the lower end of said sleeve, after which the housing cap 34 will be replaced.

Obviously, some modifications of the details herein shown and described may be made without departing from the spirit of my invention or the scope of the appended claims; and, I do not therefore wish to be limited to the exact embodiment herein shown and described.

What I claim is:

1. A valve for a liquid dispensing device adapted to be removably secured to said device, comprising a housing formed with an enlarged chamber and with a relatively large downwardly pointing mouth, a rigid sleeve removably carried by said housing and having a downwardly projecting end extending into said housing and in registration with the mouth thereof, a flexible tube carried by said sleeve and disposed within said housing, said sleeve having its lower end extending through the mouth of the housing, a housing cap screwthreaded into the mouth of the housing for supporting the lower end of said tube, said cap having a flange extending over the lower surface of said housing, said housing being formed in its lower end with a laterally arranged slot extending through one side of the wall toward the opposite side thereof, means for compressing said flexible tube to control the flow of liquid therethrough, comprising a stationary member and a movable member, each of said members being carried by said housing and disposed within the slot thereof, spring means for urging said movable member toward said stationary member, means for actuating said movable member to its open position, and detent pins carried by said housing and extending through said stationary member, said pins terminating at the lower surface of the housing and being located in that area of the lower face of the housing which is covered by the flange of the cap, whereby the pins will be retained in position.

2. A valve for a liquid dispensing device adapted to be removably secured to said device, comprising a housing formed with an enlarged chamber and with a relatively large downwardly pointing mouth, a rigid sleeve removably carried by said housing and having a downwardly projecting end extending into said housing and in registration with the mouth thereof, a flexible tube carried by said sleeve and disposed within said housing, said tube having its lower end extending through the mouth of the housing, a housing cap screwthreaded into the mouth of the casting for supporting the lower end of said tube, said cap having a flange bearing against the lower surface of said housing, said housing being formed in its lower end with a laterally arranged slot extending through one side of the housing wall toward the opposite side thereof, means for compressing said flexible tube to control the flow of liquid therethrough, comprising a stationary member and a movable member, each of said members being carried by said housing and disposed within the slot thereof, said stationary member having two oppositely arranged legs forming substantially parallel guides for said movable member, spring means for urging said movable member toward said stationary member, manually actuated means for movable member, and detent pins carried by said housing and extending through said stationary member, said pins terminating at the lower surface of the housing, and being located at that area of the lower face of the housing which is covered by the flange of the cap, whereby the pins will be retained in position.

3. A valve for a liquid dispensing device adapted to be removably secured to said device, comprising a housing formed with an enlarged chamber and with a relatively large downwardly pointing mouth, a rigid sleeve removably carried by said housing and having a downwardly projecting end extending into said housing and in registration with the mouth thereof, a flexible tube carried by said sleeve and disposed within said housing, said sleeve having its lower end extending through the mouth of the housing, a housing cap screwthreaded into the mouth of the housing for supporting the lower end of said tube, said cap having a flange extending over the lower surface of said housing, said housing being formed in its lower end with a laterally arranged slot extending through one side of the wall toward the opposite side thereof, means for compressing said flexible tube to control the flow of liquid therethrough, comprising a stationary member and a movable member, each of said members being carried by said housing and disposed within the slot thereof, said stationary member having two oppositely arranged legs forming substantially parallel guides for said movable member, spring means for urging said movable member toward said stationary member, manually actuated means for movable member, and detent pins carried by said housing and extending through said stationary member, said pins terminating at the lower surface of the housing, and being located at that area of the lower face of the housing which is covered by the flange of the cap, whereby the pins will be retained in position.

tration with the mouth thereof, a flexible tube carried by said sleeve and disposed within said housing, said tube having its lower end extending through the mouth of the housing, a cap removably disposed within the mouth of the housing and formed with an opening for the support of the lower end of the tube, said cap having a flange engageable with the lower surface of said body, said housing being formed with a laterally arranged slot extending through one side of the wall toward the opposite side thereof, a stationary pressure member carried by said housing and permanently secured in the slot thereof, said stationary member being disposed at one side of said flexible tube, a movable pressure member slidably disposed in the slot of the housing and having its inner end located on the opposite side of said flexible tube for co-action with said stationary member to compress said flexible tube, an actuating lever having an over-hanging pivot carried by said housing, said lever extending through a centrally arranged lever slot formed in the outer end of said movable pressure member, a spring slot formed in said body adjacent the pressure member slot, a tension spring disposed on each side of the lever slot and having its outer end attached to said movable pressure member, the inner end of each spring being located in the spring slot, and spring anchor pins carried by said body, each of said anchor pins being disposed in an aperture having its lower end terminating in the lower surface of said body, each anchor pin passing through the inner end of one of the springs, the flange of the cap covering the anchor pin apertures of said body and serving to retain said pins in position.

4. A valve for a liquid dispensing device adapted to be removably secured to said device, comprising a housing formed with an enlarged chamber and with a relatively large downwardly pointing mouth, a rigid sleeve removably carried by said housing and having a downwardly projecting end extending into said housing and in registration with the mouth thereof, a flexible tube carried by said sleeve and disposed within said housing, said tube having its lower end extending through the mouth of the housing, a cap removably disposed within the mouth of the housing and formed with an opening for the support of the lower end of the tube, said cap having a flange engageable with the lower surface of said

10
